UNITED STATES PATENT OFFICE.

JOHN T. DAVIS, OF NEW YORK, N. Y.

VACUUM-PUMP.

SPECIFICATION forming part of Letters Patent No. 328,469, dated October 20, 1885.

Application filed January 10, 1885. Serial No. 152,443. (No model.)

To all whom it may concern:

Be it known that I, JNO. T. DAVIS, a citizen of the United States, and a resident of New York, in the county of New York, and State 5 of New York, have invented certain new and useful Improvements in Vacuum-Pumps, Air-Compressors, and Similar Machines, of which the following is a specification.

Of the drawings, Figure 1 is a horizontal 10 section of a pump, showing piston, valves, and connections. Fig. 2 is a front end view of the same with a portion removed, showing the interior.

The same letters refer to the same parts 15 throughout.

The object of my invention is to so improve the vacuum-pump as to make it capable of producing and sustaining a more nearly perfect vacuum than has been attained heretofore. For this purpose I make the outlet-valve as large as the piston that is covering the whole end of the cylinder, and make it movable in the same direction as the motion of the approaching piston, which condenses 20 the vapor to a degree of pressure sufficient to open the valve and hold it open until the approaching piston by making actual mechanical contact with the valve has thereby expelled the last particle of the vapor, leaving 25 no clearance whatever. Thus the piston and valve form a positive close joint by the contact of their two faces, which remains until the piston, moving upon its return-stroke, permits the valve to reseat itself upon the end 30 of the cylinder. In the inner face of this discharge-valve I arrange an inlet-valve that follows the stroke of the piston as it recedes, making sufficient opening to admit the vapor to the cylinder, and remaining open until 35 the piston, having reached the opposite end of the cylinder, starts upon another forward stroke, when the inlet-valve immediately closes. By this double-valve system I secure 40 a device that will handle vapors of any degree of tension.

Figure 1 is a longitudinal section, and Fig. 2 an end view, partly in section, of my invention.

To each end of a cylinder, A, is secured, by 45 means of suitable flanges and bolts, a cylindrical shell, B, which covers the exhaust-valve C, and is provided with a nozzle, b, for

making connection with the discharge-pipe. To the outside of the shell B is secured, by similar flanges and bolts, the bonnet D, covering the inlet-valve E, and also provided with a nozzle, d, suitable for making connection with the vacuum-chamber. The discharge-valve C has a ring or cylindrical portion, c, which extends into the bonnet D, that covers the inlet-valve E, and is fitted into said bonnet by a joint packed, as at d', with any suitable material which will permit the proper motion to the valve C and at the same time prevent any communication between the bonnet D or vacuum-chamber and shell B or discharge-chamber, except through the valves C 60 and cylinder A.

In the cylinder A is a piston, F, the rod f of which passes through one of the inlet-valves 70 E and its bonnet D, and is packed at e and d' by means of stuffing-boxes and gland, in the usual manner. The packing of the inlet-valve at e steadies that valve in line and provides friction on the rod f, which assists in operating the valve, while the inlet-valve E, at the opposite end of the cylinder, is kept in position by two guide-rods, e' e', passing through the piston F and free to slide therein. The inlet-valves E are both secured to the guide-rods e', which also pass freely through a guide, c', provided in the cylindrical part c of the outlet-valve C. The function of these guide-rods e' is not only to support and align the valves E during their motion, but also to insure that motion by means of friction provided where the rods e' pass through the piston F, and also to keep the valves E at their proper distance apart, causing one to close as the other opens, and vice versa, with each 85 change of motion of the piston F.

The piston F is constructed in two parts, with an annular space, f', between them, in which is fitted a packing, f'', of leather, canvas, or other suitable material, so as to secure 90 a perfectly vapor-tight joint, the space f' being left within the packing f'' to admit a lubricating substance—as water or oil—which, permeating the leather packing, becomes effective upon the inner surface of the cylinder 100 A. An oil-way or "limber," f', is also provided in the piston-rod F and the hub of the piston, by means of which the lubricating-fluid may be introduced, as required, while in

operation, without affecting the vacuum, as would necessarily be the case if oiled through the cylinder in the usual manner.

An elastic-ring packing, f^4 , is provided in the cylinder F, and, surrounding each of the guide-rods e' , performs the double function of making an impervious joint, and also supplying the requisite friction to operate the valves, as described.

10 The faces of the piston and valves and their seats are cushioned with a sheet of rubber, f^5 , or other suitable material, for the purpose of both deadening the blow and perfecting the contact when they come together, as described.

15 The exhaust-valves C are also provided with springs c^2 , which assist the back pressure of the discharge-chamber in closing the valve as

the piston withdraws, insuring their perfect action.

Having thus described my invention, what I claim is—

In a pump for elastic vapors, the combination of the valves E, guide-rods e' , packing e , piston F, rod f , packing f^4 , guide c' , and valve C, when the motion of the piston is utilized to actuate the valves, as and for the purposes herein shown and described. 25

Signed at New York, in the county of New York, and State of New York, this 5th day of January, A. D. 1885.

JNO. T. DAVIS.
